UNITED STATES PATENT OFFICE

163,743

CONFECTION

Jan Boon, Ardsley-on-Hudson, N. Y.

Application June 21, 1950, Serial No. 10,674

Term of patent 14 years

(Cl. D82—2)

To all whom it may concern:

Be it known that I, Jan Boon, a subject of the Queen of the Netherlands and residing in Ardsley-on-Hudson, county of Westchester, State of New York, have invented a new, original, and ornamental Design for a Confection, of which the following is a specification, reference being made to the accompanying drawing, forming part thereof.

Fig. 1 is a front elevational view of the confection showing my new design;

Fig. 2 is a side elevational view; and

Fig. 3 is a top plan view thereof.

The dot-dash lines in the central portion of Figs. 1 and 2 outline a design of tulip leaves which is optional for incorporation in said central portion. The dominant features of the design are shown in full lines.

I claim:

The ornamental design for a confection, substantially as shown and described.

JAN BOON.
